UNITED STATES PATENT OFFICE.

EDWARD B. HODES, OF CHICAGO, ILLINOIS, ASSIGNOR OF ONE-HALF TO CHARLES A. LAWES, OF CHICAGO, ILLINOIS.

DRAW-SHEET GUIDE.

1,368,930.

Specification of Letters Patent. Patented Feb. 15, 1921.

Application filed November 15, 1918. Serial No. 262,672.

To all whom it may concern:

Be it known that I, EDWARD B. HODES, a subject of the Russian Government, residing at Chicago, in the county of Cook and 5 State of Illinois, and having filed my first papers to attain naturalization in the United States, have invented certain new and useful Improvements in Draw-Sheet Guides, of which the following is a description.

10 My invention belongs to that general class of devices attached to a suitable sheet, and placed in the usual type of platen press to serve as a guide to the several sheets as they are placed therein. It has for its object a 15 simple and effective device of the class described adapted to be readily and reliably adjusted from time to time as may be necessary.

To this end my invention consists in the 20 novel construction, arrangement and combination of parts herein shown and described and more particularly pointed out in the claims.

In the drawings, wherein like reference 25 characters indicate like or corresponding parts,

Figure 1 is a plan view of a base sheet showing two of my improved guides in place thereon;

30 Fig. 2 is a partial sectional view taken substantially on line 2—2 of Fig. 4 to show the preferred means of positioning a coöperating vertical guide therefor;

Fig. 3 is a section taken substantially on 35 line 3—3 of Fig. 2;

Fig. 4 is a section taken substantially on line 4—4 of Fig. 2;

Fig. 5 is a plan view showing the device 40 partially open ready for positioning in place; and

Fig. 6 is a plan view partially broken away to show a modification.

In the drawings, 1 is a suitable sheet of paper or other material upon which the various sheets are placed as they are presented to the press. As shown, at preferably a plurality of points the sheet is cut or slit as at 2—2 to provide a section 3 attached at each end of the main sheet 1, forming substantially a tongue, but beneath which the base of my improved guide may be placed. The base 4 (Fig. 4) is slipped beneath the tongue 3 with its elevated or thickened portions 5 resting upon the top of the sheet 1. A latch 55 piece 6 is pivotally connected to the base

piece at one end as at 7, preferably having ends reduced as at 8—8 to be positioned within transverse slots formed in the thickened ends 5. The approximate meeting faces on the latch 6 and the base 4 are preferably beveled or otherwise formed, so that as the free end 8 is forced into the slot as indicated at the right-hand of Fig. 4, it will serve to cause the latch and the base to firmly grip the part 3 of the sheet 1 therebetween and reliably maintain the guide in proper position to perform its function. The thickened edges 5 as at 9—9 (Figs. 2 and 6) serve as the guiding pieces for the sheet which is to be submitted to the press. 60 65 70

It will be readily seen as thus described that when it is desired to detach the guides it is only necessary to force the latch 6 together as indicated in Fig. 5, thereby releasing the sheet gripped between the latch 75 and the base, and permitting a slight lifting of the part 3 with the removal of the guide therefrom.

In some cases it is also important to provide an additional guide having the function to hold the paper sheet down and preventing it from riding over the upper edge of the guides 9—9. This may be accomplished in any preferred manner. 80

I have secured satisfactory results in the 85 manner indicated in Figs. 2 to 6 inclusive, in which I have formed a transverse slot 10, or the equivalent, through the latch 6 and secured a guiding member 11 therein with its end projecting beyond the face 9. I prefer to detachably position the guide 11 in the latch, and one simple means is indicated in the drawings. Referring particularly to Fig. 2, I place a pin 12 or equivalent part near one side of the slot 10 and the latch 6, 90 and form the guide 11 with one or more notches 13 therein adapted to engage with the pin 12. A suitable spring device 14, adapted to engage the other wall of the slot, serves to force the guide 11 toward the opposite wall of the slot with the notch embracing the pin 12. I prefer to extend the end of the spring as at 15 beyond the face of the latch, so that with the thumb and finger the spring may be compressed and the 100 guide removed from the slot. I also prefer that the guide 11 shall be of light metal, although any material that will perform the 105 function may be employed.

The entire device is extremely simple and 110

economical in construction, and very effective for the purpose described.

In the form shown in Fig. 6, I have provided simple means to serve to initially move the latch member in relation to the base member to disengage the free end of the latch. As here shown, I form a slot or opening through the thickened end of the base as at 16 and position therein a lever 17 pivotally maintained in place as at 18, with the free end 19 extended and adapted to contact with the free end of the latch. Pressing the end 17 of the lever toward the front of the device will thus serve to force the free end of the latch out, serving to aid in the easy disengagement of the latch from the base. As the parts are rather small this lever arrangement to initially disengage the parts is some times a considerable convenience.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:—

1. In a device of the kind described, a base piece formed to constitute a guide in combination with a latch piece pivotally connected at one end thereto, adapted to swing in a plane parallel to that of the base to normally lie in close proximity to the base to grip a sheet of material positioned between the two, means for reliably maintaining the two in such relation, and supplemental means for initially forcing the free end of the latch member outward to disengage the latch from the base.

2. In a device of the kind described, a base piece forming a guide and having slots formed in the two ends thereof, in combination with a latch piece having its ends reduced to be loosely positioned within the slots, one end of the latch being pivotally connected to the base, the approximate faces of the base and latch being inclined to approach each other as the latch is forced into engaging relation with the base.

3. In a device of the kind described, a base piece formed to constitute a guide, in combination with a latch piece pivotally connected at one end thereto adapted to swing in a plane parallel to the base and normally lying in close proximity to the base to grip a sheet of material positioned between the two, means for reliably maintaining the two in such relation, and a supplemental lever accessible from the outer side of the base arranged to operate to force

the upper end of the latch out of engagement with the base.

65

4. In a device of the kind described, a base piece arranged to provide a guide for a sheet of paper, in combination with a latch piece pivotally connected at one end thereof adapted to normally lie in close proximity to the base to grip a sheet of material positioned between the two, means for reliably maintaining the two in such engaged relation, and a supplemental guide carried by the latch piece and extending at right angles thereto and arranged to prevent the sheet of paper from rising over the edge of the guide.

70

5. In a device of the kind described, a base piece arranged to constitute a guide for a sheet of paper, in combination with a latch piece pivotally connected at one end to the base and adapted to swing in a horizontal plane to normally lie in close proximity to the base to grip a sheet of material positioned between the two, means for reliably maintaining the two in such relation, and a supplemental piece adjustably mounted on the latch and arranged to prevent the escape of paper over the edge of the guide, and resilient means for maintaining said guide 90 in its different positions of adjustment.

85

6. A device of the kind described comprising a base adapted to provide a sheet guide, a latch piece connected with said base and capable of a movement relative thereto, said latch piece being normally adapted to lie in a plane parallel with the base and in close proximity thereto, the latch piece having a transverse slot therein, a supplemental guide mounted in said slot, and means for holding 100 said guide in its different adjusted positions relative to the latch piece.

95

7. A device of the kind described comprising a base adapted to provide a sheet guide, a latch piece connected with said base and capable of a movement relative thereto, said latch piece being normally adapted to lie in a plane parallel with the base and in close proximity thereto, the latch piece having a transverse slot therein, a supplemental guide 110 mounted in said slot, and means for holding said guide in its different adjusted positions relative to the latch piece, said means comprising a pin carried by the latch piece adapted to engage sockets in the side of the supplemental guide, and resilient means for maintaining the guide in proper relation with said pin.

115

In testimony whereof, I have hereunto signed my name in the presence of two subscribing witnesses.
